UNITED STATES PATENT OFFICE.

FREDERICK JAMES REED AND JOHN STYLE REED, OF SOUTHAMPTON, ENGLAND.

ELECTRICALLY-HEATED VAPORIZER FOR INTERNAL-COMBUSTION ENGINES.

Application filed March 25, 1922. Serial No. 546,572.

To all whom it may concern:

Be it known that we, FREDERICK JAMES REED and JOHN STYLE REED, subjects of the King of Great Britain, and residents of Southampton, in the county of Hants, England, have invented certain new and useful Improvements in Electrically-Heated Vaporizers for Internal-Combustion Engines, of which the following is a specification.

- 10 This invention relates to devices for igniting and vaporizing the fuel in internal combustion engines and especially in engines of the semi-Diesel type and has for its object to provide an improved device which is particularly adapted for the vaporization of 15 heavy fuels in automobile and similar engines and the temperature of which is automatically regulated according to requirements caused by the variations in temperature 20 in the cylinder due to changes in the engine load and speed.

In the accompanying drawings in which similar reference characters relate to corresponding parts throughout the several figures 25 thereof—

Figures 1 and 2 represent a sectional elevation and part plan respectively of one form of construction of a vaporizer in accordance with our invention.

30 Figure 2 being a section on the line A—A, Figure 1.

Figure 3 is a sectional elevation and

35 Figure 4 a part section of an alternative and preferred form of construction of vaporizer particularly adapted for automobile, aeronautical and like engines.

Referring to the said drawings and particularly to Figures 1 and 2 it will be seen that the vaporizer shown in these figures 40 comprises a plug formed in two parts *a* and *b* the lower part or body *a* being screwed into the cylinder cover *c* whilst the upper part or cap *b* is screwed into and bears upon a seating *e* in the body *a* a fibre washer *f* being interposed between the two parts *a* and *b*.

45 The body *a* is formed with a hollow bulb *g* which is packed with suitable material such as insulating clay or porcelain *h* in 50 which is inserted a carbon resistance *i* which is preferably arranged as shown in the form of a spiral disposed around a central metallic rod *j* and terminating at the point *k* in the lower wall of the bulb *g*.

55 The ignition wire *l* is attached to a rod *m* which passes through an insulating plug *n*

inserted in the bushing *o* which is screwed into the wall *p* of the cap *b*, and the head *q* of the rod *m* bears against the head *r* of a pivotably mounted rocking lever *s* the 60 lower portion of said lever normally bearing upon and being in contact with the top of the rod *j*. The rod *j* is in two parts composed of metals having different coefficients of expansion under the influence of the 65 heat the upper part *t* of said rod being of copper with an insulated knob *u* at the top which as stated above bears against the bottom of the rocking lever *s* whilst the lower part *v* and the fins *w* attached thereto are 70 of steel.

75 Current passes from a battery or other suitable source through the ignition wire *l* to the insulated rod *m* the rocking lever *s* and the rod *x* on which it is pivotally mounted to the carbon resistance *i* making the same and the bulb *g* red hot and causing an arc between the lower end of the carbon spiral and the wall of the bulb *g* at the point *k* which places the portion of the bulb *g* 80 at this point in a state of incandescence.

85 The fuel valve is disposed at *y* so that the fuel impinges directly on the point *k* of the bulb *g* and is immediately ignited. After a few such ignitions of the fuel the whole of the plug becomes sufficiently heated and electrical heat is therefore unnecessary the heat of the combustion in the cylinder maintaining the bulb *g* at the requisite temperature. The current is then automatically cut 90 off in the following manner. The rod *j* expands under the influence of the heat and more particularly the upper portion *t* formed of copper consequently it rocks the rocking lever *s* and moves the head *r* thereof out of contact with the head *q* of the insulated rod *m* thus breaking the electrical connection and cutting off the current from the carbon spiral *i*. In the event of the 95 engine running slow or being stopped the connection is re-established due to the contraction of the rod *j* as will be obvious without further explanation.

If the engine is given an extra load the bulb *g* and the rod *j* may possibly get overheated causing difficulties with the plug and the engine and to avoid this grave disadvantage the following arrangement is adopted as shown.

100 Adjacent to and in the path of movement 110 of the rocking lever *s* is a wedge-shaped fibrous block *z* pivoted at *1* to the block *2*

which is adjustably mounted in a sleeve 3 integral with the cap *b* and maintained in position by the spring 4, the block *a* being in contact with a ball valve 5 closing the orifice 6 for the admission of compressed air through the pipe 7.

In the event of undue expansion of the rod *j* due to over heating the consequent oscillation of the lever *s* forces the block *a* against the ball valve 5 unseating the ball and allowing air to pass through the body of the plug and cool the bulb, the air flowing through the passage *d* around the fins *w*, thence through passage 35 to and around the carbon spiral *i* and passing out through the passage 36.

In Figures 3 and 4 we have shown an alternative form of construction of vaporizer adapted for automobile, aeronautical and like engines. The bulb *g* packed with the insulating material *h* and the walls of which are provided with the spirally disposed vanes 8 is disposed within a cylindrical container 9 divided into two compartments 10 and 11 by the vertical wall 12, and enclosed within a cylindrical casing 13 provided with the cover 14. The bulb *g* which is surrounded by the cap *b* depends within the compartment 10 while the adjacent compartment 11 forms a gas cylinder or holder within which the piston 15 moves and from the upper part thereof the outlet pipe 16 leads to the engine cylinder.

The upper end of the piston rod 17 is attached to one end of a rocking lever 18 fulcrumed at 19 the other end of which is attached to the upper end of a vertical rod 20, the lower end of the rod 20 being normally in contact with a ball 21 closing the fuel valve 22 which controls the admission of the fuel, such as a heavy oil, from the pipe 23 under pressure to the pipe 24 spirally disposed around the wall of the container 9 and terminating at the discharge nozzle 24^a.

45 The carbon resistance *i* is in the form of a wedged shaped block so as to be self adjusting and is disposed immediately opposite the orifice of the discharge nozzle 24^a and within the insulating material *h*. The construction and arrangement of the central rod *h* the rocking lever *s* the ignition wire *l* and the insulated rod *m* are the same as described in connection with the form of vaporizer shown in Figure 1 the electric current passing to the carbon block *i* and the bulb *g* and making the wall of the latter extremely hot and being cut off automatically when the heat is sufficient to maintain the bulb at the requisite temperature.

50 The suction of the engine causes a partial vacuum to be formed in the induction pipe 16 causing the piston 15 to ascend, air being admitted to the underside of the piston through the inlet 25, thus rocking the lever 18 which by means of the rod 20 forces the

ball 21 of the fuel inlet valve 22 off its seat and admits the fuel to the spiral pipe 24 which passes therethrough to the nozzle 24^a and is discharged from thence in the form of a fine spray against the wall of the bulb *g* at the point *k* and is immediately vaporized.

55 The air inlet valve 26 (Figure 4) is disposed in the lower part of the wall of the compartment 10 below the nozzle 24^a and is opened by the partial vacuum in the induction pipe to allow a certain quantity of air, the amount of which can be regulated by rotation of the covering cap 27 operated by the lever 28, to pass into the passages 29 between the wall of the compartment 10 and the bulb and between the vanes 8 and there mixes with the vaporized fuel forming a highly explosive gas which passes through the passages 29 and the port 30 in the wall 12 into the gas chamber 11 and from thence through the pipe 16 to the engine cylinders as fuel. The oil which does not vaporize collects in the bottom of the compartment 10 where it is subsequently vaporized by the heat caused by the exhaust gases which enter the vaporizer at 31 pass around passages 32 formed between the wall of the container 9 and the wall of the outer casing 13 by the vanes 33 and pass out by the outlet 34. These exhaust gases in the course of their 60 passage as described materially heat the whole body of the vaporizer maintaining the bulb at the requisite temperature, the wall of the outer casing 13 being covered with asbestos to prevent loss of heat by 65 radiation.

What we claim is:—

1. The combination with an electrically heated vaporizer for internal combustion engines comprising a bulb, a packing of insulating material within said bulb, a carbon resistance disposed in said insulating material, means for passing an electric current through said carbon resistance and means whereby a hot point is formed on the wall 110 of said bulb of means for automatically cutting off said electric current when a requisite temperature has been attained thereby.

2. The combination with an electrically heated vaporizer for internal combustion engines comprising a bulb, a packing of insulating material within said bulb, a carbon resistance disposed in said insulating material, means for passing an electric current through said carbon resistance, means 115 whereby a hot point is formed on the wall of said bulb and means for spraying liquid fuel on said hot point of means for automatically cutting off said electric current when a requisite temperature has been attained thereby.

3. The combination with an electrically heated vaporizer for internal combustion engines comprising a bulb, a packing of insulating material within said bulb, a carbon 120

resistance disposed in said insulating material, means for passing an electric current through said carbon resistance, means whereby a hot point is formed on the wall 5 of said bulb and means for spraying liquid fuel on said hot point of a composite metallic rod, a pivotally mounted rocking lever contacting with the head of said metallic rod and an insulated rod contacting with the 10 head of said rocking lever.

4. The combination with an electrically heated vaporizer comprising a cylindrical container divided into two compartments, a bulb arranged in one of the said compartments and a gas reservoir in the other of said compartments, a piston operating in said reservoir, a fuel inlet valve, a fuel pipe spirally disposed around said cylindrical container and connections between said piston and said fuel inlet valve of means for automatically cutting off the electric current when a requisite temperature has been attained. 15

5. The combination with an electrically heated vaporizer comprising a cylindrical 20

container divided into two compartments a bulb arranged in one of the said compartments, a packing of insulating material within said bulb, a carbon resistance disposed within said insulating material, means for passing an electric current through said carbon resistance, means whereby a hot point is formed on the wall of said bulb, a gas reservoir in the other of said compartments, a piston operating in said reservoir, a fuel inlet valve, a fuel pipe spirally disposed around said cylindrical container, connections between said piston and said fuel inlet valve, means for spraying fuel from said spirally disposed pipe on said hot point and an air inlet valve, of a composite metallic rod, a pivotally mounted rocking lever contacting with the head of said metallic rod and an insulated rod contacting with the 30 head of said rocking lever. 35

In testimony whereof we affix our signatures. 40
